(57) **CLAIM**

The ornamental design for a wooden turntable, as shown and described.

DESCRIPTION

FIG. 1 is a perspective view of a wooden turntable showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the wooden turntable; and,

FIG. 10 is an enlarged view of portion 10 shown in FIG. 9. The broken lines shown in the drawings depict portions of the wooden turntable that form no part of the claim. The dot-dash-dot lines marking the location of the enlargement form no part of the claim.
